UNITED STATES PATENT OFFICE.

STEPHEN P. BROWN, OF STRATFORD, CONNECTICUT.

LAMINATED MULTIPLE-ARCH CONCRETE DAM.

No. 818,738.

Specification of Letters Patent.

Patented April 24, 1906.

Application filed April 10, 1905. Serial No. 254,789.

To all whom it may concern:

Be it known that I, STEPHEN P. BROWN, a citizen of the United States, residing at Stratford, in the county of Fairfield and State 5 of Connecticut, have invented a new and useful Improved Laminated Multiple-Arch Concrete Dam; and I do hereby declare the following, when taken in connection with the accompanying drawings and the figures of 10 reference marked thereon, to be a full, clear, and exact description of the same, and which said drawings constitute part of this specification, and represent, in—

Figure 1, a broken plan view of a dam constructed in accordance with my invention; 15 Fig. 2, a broken view thereof in elevation looking toward its downstream face; Fig. 3, an enlarged view in vertical section on the line *a b* of Fig. 1.

20 My invention relates to an improved multiple-arch concrete dam, the object being to produce at a relatively small outlay for labor and material a dam not only of sufficient power to resist very high pressures, but also 25 of great durability on account of the adaptation of some of its members to independently contract and expand, and thus accommodate themselves to disrupting forces or conditions which, if not so accommodated, would tend 30 to impair the integrity of the fabric.

With these ends in view my invention consists in a multiple-arch concrete dam having certain details of construction, as will be hereinafter described, and pointed out in the 35 claims.

In carrying out my invention, as herein shown, I construct a series of arches 2, arranged end to end in a horizontal plane with their convex faces turned upstream toward 40 the pressure of water impounded by the dam and springing between piers 3, spaced across the dam-site and end abutments 4. The arches 2 will rest on table-like foundations 5 of massive or reinforced concrete construction 45 and conforming to them in curvature. The piers 3 and end abutments 4 (only one of the end abutments is shown) will be built of massive concrete firmly anchored to the bedrock, preferably by heavy steel expansion- 50 bolts, and held against sliding by steel shearing-pins. Such bolts and steel shearing-pins, being of well-known concrete construction, are not shown. The arches 2 will be built 55 continuous or integral with the said piers and end abutments, but instead of being of massive concrete construction will be of rein-

forced concrete construction—such, for instance, as ferroconcrete illustrated by bent steel rods 6, embodied in the concrete. The arches are not monolithic but laminated, 60 each arch consisting of a vertical series of arch members 7, superimposed upon each other and free to move laterally independently of each other. At their ends these arch members merge into the piers 3 and end abutments 4, with which they are made, as it were, in one piece. The dimensions of the arches will vary according to the dictation of circumstances. It will be quite feasible to make the arches thirty-feet span or over. 70 The arch members (probably about five feet thick) will be separated by a thin film or layer 8 of asphalt, applied as they are completed one after the other, working from the lowest member upward and forming a shearing-surface for the free articulation of the arch members one upon the other as the individual arch members are exposed to conditions which make them contract and expand differentially. This differential movement of the arch members will not of course be great, but it will be sufficient to provide for just that accommodation of the structure to disturbing forces which, if not accommodated, would prove gradually disruptive of 80 the integrity of the fabric. As shown, the arch members are separated from each other on the upstream face of the dam by wedge-like grooves 9, formed by beveling the lower corners of the arch members. These grooves 90 may be filled with suitable calking material to insure a water-tight joint, and in any event will act as "catchalls" for the self-calking of the fabric in cases of small leaks. Of course the number of arches, the length of their 95 span, the number of arch members, and so on will be determined by the circumstances of each particular case, my invention being unlimited in this respect. As shown, the arches are arranged in a horizontal plane. 100 This is not essential, however, so long as the convex faces of the arches are against the water-pressure. I would, therefore, have it understood that I do not limit myself to the exact construction herein shown and described, but hold myself at liberty to make such departures therefrom as fairly fall within the spirit and scope of my invention. 105

Having fully described my invention, what I claim as new, and desire to secure by Letters Patent, is—

1. A laminated arch for concrete dams,

the said arch consisting of a plurality of arch members superimposed one above the other and movable laterally for the accommodation of forces tending to disrupt the fabric of the arch.

2. A laminated arch for concrete dams, the said arch consisting of a plurality of arch members superimposed one above the other and movable laterally with respect to each other and separated by films of asphalt.

3. A laminated arch for concrete dams, the said arch consisting of a plurality of arch members superimposed one above the other and movable laterally with respect to each other and having their upstream faces separated by grooves for the reception of calking and to act as self-calking "catchalls."

4. A laminated multiple-arch concrete dam consisting of a series of arches arranged with their convex faces against the water-pressure and supported by piers and end abutments, each arch consisting of a plurality of arch members superimposed one above the other and movable laterally with respect to each other for the accommodation of forces tending to disrupt the fabric of the dam.

In testimony whereof I have signed this specification in the presence of two subscribing witnesses.

STEPHEN P. BROWN.
